FREQUENCY CONTROL SYSTEM

William S. Marks, Jr., Long Branch, N. J.

Application November 6, 1942, Serial No. 464,755

4 Claims. (Cl. 250—36)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a radio frequency wave generating system and more particularly to a system for deriving a series of stable frequencies to be used for transmitter excitation and related purposes.

Transmitters by which a series of waves of different frequencies are propagated often incorporate therein a plurality of crystals serving to control oscillator stages so as to stabilize the output of the transmitter at each particular frequency thereof. Such transmitters ordinarily employ a separate crystal for each desired frequency inasmuch as the units of the desired frequency series are usually spaced from each other by comparatively small amounts and are not integral multiples of the crystal frequency. If, for example, 80 frequencies were desired having the stability of a crystal controlled oscillator and wherein said frequencies were spaced from each other by amounts appreciably smaller than that of the crystal frequency so that the units of the series were not integral multiples of the crystal frequency, it would be ordinarily necessary to employ substantially 80 crystals wherein each crystal controlled oscillator determined a particular frequency in the series.

Operations based upon the selection of harmonics of the crystal frequency obviously cannot satisfy the requirements when frequencies spaced by amounts less than that of the crystal frequency are desired.

The use of a multivibrator to derive frequencies spaced by submultiples of a crystal controlled oscillator is known but if it were desired to derive a series of spaced frequencies in, for example, the 10 to 20 megacycle band, an extremely high harmonic of the multivibrator output would have to be selected. Assuming that the multivibrator frequency is 50 kilocycles it would require at least the 200th harmonic and would be impracticable for an ordinary transmitter system.

Furthermore, in operating at these high order harmonics, the relative frequency separation becomes increasingly smaller, and the isolator or filter circuits for selecting the appropriate harmonics must be extremely sharp and critical to distinguish between them. Such conditions are difficult to meet due to the required delicacy of design and adjustment. This difficulty is particularly marked in the use of remote control and push button tuning mechanism since slight

irregularity in the transmission means such as may be due to back lash in the gears may detune the selector stages from the required setting.

Bearing the foregoing in mind, the present invention is concerned with the provision of a series of frequencies which are controlled as to stability by the use of a crystal controlled oscillator wherein a single crystal suffices to stabilize every unit frequency in the series, which unit frequencies are not limited to integral multiples of the crystal frequency. While a multivibrator is utilized in deriving frequencies spaced by a submultiple of the crystal frequency, the present invention makes it unnecessary to employ unduly high harmonics of the multivibrator output to attain relatively high frequencies.

The frequencies derived by the instant invention are not only crystal controlled but have no original source of oscillations other than the crystal controlled oscillator so that variations in the crystal controlled oscillator cannot conflict with the frequencies from any other source to produce beat notes or other undesirable results. Since the original source is a single crystal controlled oscillator, variations thereof are uniform throughout the system. Such variations, moreover, may be minimized by conventional means such as by thermostatic temperature control.

As is well-known, crystal controlled oscillators are often provided with temperature control means to minimize frequency variations due to temperature changes. Crystals of different frequencies may require different conditions of such temperature control since crystals have individually varying temperature coefficients. In a transmitter having a large number of crystals, the problem is of considerable magnitude and is often partially solved by utilizing temperature control means adapted to all of the crystals involved. The tolerances thereof must be widened to accommodate all of the crystals and obviously cannot allow rigid control of anyone of them. According to the present invention, however, such control may be made as rigid as desired since only one crystal is to be controlled by the temperature control means.

Other and further objects and advantages will be pointed out hereinafter and the novel features thereof set forth in the appended claims.

In describing the details of the invention reference is made to the drawing wherein:

Figure 1 is a block diagram illustrating an embodiment of the invention; and Figure 2 illustrates a modification thereof.

Referring to Figure 1, the source of oscilla-

tions comprises a crystal controlled oscillator 10, having a frequency which, in the typical embodiment illustrated, may, for example, be 500 kilocycles. The crystal controlled oscillator 10 serves as the source of wave generation for both channels of the system as will be hereinafter described.

Referring to channel A, the crystal controlled oscillator 10 feeds into and controls a multivibrator 11, the fundamental frequency of which is a sub-multiple of the oscillator frequency, in the present instance 50 kilocycles. The output of multivibrator 11 is connected to a selector or amplifier selector 12 which may be tuned to any one of a series of harmonics of the 50 kilocycle multivibrator in a defined band width extending in frequency from 2 to 3 megacycles so that the output of the selector 12 is 2.00 mc., 2.05 mc., 2.10 mc., 2.15 mc., etc. up to 3.0 mc., representing, respectively, the 40th to 60th harmonic of the multivibrator 11.

The desired harmonic is then selected and amplified in the amplifier selector 12 and, representing the output of channel A, is fed into a mixer 13 where it is heterodyned in conventional manner with another frequency supplied by channel B of the system.

Channel B includes a doubler 14 and a frequency multiplier 15, the combination of which serves to derive frequencies of 8, 9, 10, or 11 megacycles from the output of the oscillator stage 10. The doubler 14 raises the original frequency to twice its value, so that the multiplier 15 selects the 8th to the 11th harmonics of the output of the doubler 14, which harmonics are spaced by a full megacycle.

The output of the frequency multiplier 15 is then fed into the mixer 13 where it is heterodyned with the output of the amplifier selector 12. The output of the mixer 13 is tuned to select the beat frequency produced, for example, by the addition of the frequencies fed in by both channels. The output of mixer 13 will therefore be in the 10 to 14 megacycle range, the particular output frequencies obtainable being spaced apart by 50 kilocycles throughout the range. Thus, any one of a series of 80 predetermined and uniformly spaced frequencies may be produced, all of which are crystal controlled as to stability and are derived from a single source, but which are not necessarily integral multiples of the crystal frequency.

A particular advantage of the construction hereinabove set forth is the simplification of the mixer stage 13 made possible by the fact that a high degree of selectivity is not required and the required selection is easily accomplished. This result is attributable to the fact that when the mixer 13 is tuned to select a specific beat frequency of the series, the nearest other frequency which is present in the mixer stage is removed from the desired frequency by a substantial amount. This amount is represented by the output frequency of the amplifier selector stage 12.

It will be noted that channel A, although providing the source of sub-multiple differences, has an output which is appreciably higher in frequency than that of the crystal oscillator. This is of advantage effecting as it does a substantial difference between the frequencies present in the mixer stage 13. On the other hand, the output of channel A is of sufficiently low frequency so as not to require relatively high harmonics of the multivibrator output. Thus, sufficient excitation voltage for the selector stage 12 is provided. It also follows that the selec-

tivity of the amplifier selector stage 12 need not be excessive since only the 40th to the 60th harmonic of the multivibrator output is selected.

The output of channel A being in the 2 to 3 megacycle range, the nearest frequency to that of the desired one is spaced therefrom by at least two megacycles. As above stated, the selectivity of the mixer stage 13 need not be critical since it is only required to distinguish between widely separated frequencies. The system is therefore feasible where mechanical remote control or push button tuning means are used even should the tuning means employed cause deviation from the critical adjustment of the tuning units due to irregularities in the mechanical transmission.

Figure 2 illustrates a modification of the invention. As an example of this modification, the output of a 500 kilocycle crystal controlled oscillator 16 feeds into and controls a multivibrator 17. The amplifier selector 18 is tunable to a frequency range of from 2 to 2.5 megacycles in steps of 50 kilocycles. The multivibrator 17 may operate, for example, at a fundamental frequency of 50 kilocycles so that the harmonic output frequencies of the amplifier selector 18 may be spaced 50 kilocycles apart.

Channel D includes a frequency multiplier 19 fed from the oscillator 16. Multiplier 19 may assume a conventional form and serves to select the sixteenth to twenty-second harmonic of the 500 kilocycle initial crystal frequency. Frequencies of 8, 8.5, 9, 9.5, 10, 10.5 and 11 are secured as desired and fed to the mixer 20 there to be heterodyned with the output of channel C. The output of mixer 20 is tunable to derive the desired additive frequencies in the range of 10 to 14 megacycle spaced 50 kilocycles apart.

Both systems hereinabove described are similar in that same output frequencies are secured therefrom, the difference being that in the example shown in Figure 2 the multivibrator channel need only cover a range of half a megacycle since the frequency multiplier channel is divided into half megacycle differences within its range. Either system may be varied to derive wider or narrower bands with a greater or smaller number of frequencies involved, or may employ different combinations to derive the same frequencies, the examples given being illustrative of the utility and operation of the system. Both systems produce a large number of crystal controlled frequencies, which frequencies are not necessarily integral multiples of the single crystal employed.

The frequencies derived may be used for transmitter excitation or other purposes where a series of stable frequencies within a limited range are required. In the case of a transmitter, the crystal controlled oscillator may be phase or frequency modulated before being multiplied in either channel B or channel D. When the crystal controlled oscillator is phase or frequency modulated before being multiplied, the invention presents particular advantages since the frequency of the phase or frequency modulated carrier wave may be increased or decreased by beating it with the output of channel A or channel C without, however, affecting the deviation range of modulation. Crystal controlled frequency changes without affecting this deviation range is made possible by this invention while utilizing only one crystal to effect a variety of such frequency changes.

Suitable amplifiers may be used after the mixer

stage to raise the output voltage to a desired amplitude and multipliers may be used as desired to effect further frequency increases.

While I have illustrated and described the output of the mixer stages as being tuned to select the additive beat frequencies, it is apparent that the system is flexible enough to conform to many requirements such as the selection of the difference beat frequencies or any other frequencies present in the mixer stages.

I have described preferred embodiments of this invention, but it will be obvious to those skilled in the art that various changes and omissions may be made therein without departing from the invention, and it is therefore aimed in the appended claims to cover all such change and modifications as fall within the true spirit and scope of the invention.

I claim:

1. An alternating current system comprising a pair of channels fed in parallel from a source of alternating current, means in one of said channels and under the control of said source for generating waves having a fundamental frequency which is a submultiple of the frequency of said source and rich in harmonics of said submultiple frequency, means connected solely to the output of said last named means to filter any one of a series of contiguous submultiple harmonics within a first frequency band which is higher than the frequency of said source, means in the other of said channels and controlled by said source for generating a wave having a frequency which is a multiple of the frequency of said source and which is higher than any of the harmonics in said first band and displaced therefrom by an interval which is equal to at least several times the frequency of said source, and a mixer energized by a selected harmonic in the first channel and the multiple frequency output of said second channel.

2. A high frequency alternating current system comprising a pair of channels fed in parallel from a source of alternating current, means in one of said channels and under the control of said source for generating waves having a fundamental frequency which is a submultiple of the frequency of said source and rich in harmonics of said submultiple frequency, means connected solely to the output of said last-named means to select any one of a series of contiguous submultiple harmonics within a first frequency band which is higher than the frequency of said source, means in the other of said channels and controlled by the output of said source to generate a plurality of waves having frequencies which are multiples of the frequency of said source, said multiples lying in a second frequency band which is displaced from said first frequency band by an interval which is equal to at least several times the frequency of said source, and a mixer energized by a selected harmonic in the first channel and a predetermined multiple in

said second channel to derive beat frequencies of the currents fed therein, and means to select one said beat frequencies.

3. A high frequency alternating current generating system comprising in combination a relatively stable source of sine wave oscillations, a pair of mutually independent channels fed from said source, a non-sinusoidal wave generator in one of said channels and under the control of 10 said oscillations for generating waves having a fundamental frequency which is a submultiple of the frequency of said oscillations, means connected solely to the output of said generator to select and amplify any one of a series of contiguous harmonics of said submultiple frequency lying within a first frequency band which is higher than the frequency of said source, means in the other of said channels and controlled by the output of said source for generating a plurality of waves having frequencies which are multiples of the frequency of said source, said multiples lying in a second frequency band which is higher than said first band and displaced therefrom by an interval which is equal to at least several times the frequency of said source, the width of said first band being at least equal to the frequency of said source, a mixer energized by a selected harmonic in the first channel and a predetermined multiple in said other channel to derive beat frequencies of the currents fed therein, and means to tune said mixer to select one said beat frequencies.

4. A high frequency alternating current generating system comprising in combination a stabilized source of sine wave oscillations, a pair of mutually independent channels fed from said source, a multivibrator in one of said channels and under the control of said source for generating waves having a fundamental frequency 35 which is a submultiple of the frequency of said oscillations, means connected solely to the output of said multivibrator to filter and amplify any one of a series of contiguous harmonics of said submultiple frequency lying within a first frequency 40 band which is higher than the frequency of said source, a frequency doubler under the control of said source in the other of said channels, means controlled by the output of said doubler to generate a plurality of waves having frequencies which are multiples of the frequency of the 45 output of said doubler, said multiples lying in a second frequency band which is higher than said first band and displaced therefrom by an interval which is equal to at least several times the frequency of said source, the width of said first band being at least equal to the interval between said multiples, a mixer energized by a filtered harmonic in the first channel and a selected multiple in said other channel to derive beat frequencies of the currents fed therein, and means 50 to tune said mixer to select one said beat frequencies.
